UNITED STATES PATENT OFFICE

OTTO BAMBERGER, OF DUISBURG, GERMANY, ASSIGNOR TO DEUTSCHE MASCHINEN-FABRIK AKTIENGESELLSCHAFT, OF DUISBURG, GERMANY

PILGERING MILL

Application filed March 25, 1926, Serial No. 97,329, and in Germany February 6, 1926.

The present invention relates to driving gear for the feeding mechanism of pilgering mills.

Hitherto the various movements of the feeding mechanism were effected by hydraulic means.

The method of operating the feeding mechanism renders necessary varying powers and speeds. On the one hand the blank, which is placed upon the mandrel, is very quickly rolled, while on the other hand the actual pilgering proceeds slowly in exactly uniform finely graduated forward movements of the blank. After the tube has been rolled, the feeding mechanism is used for withdrawing the mandrel from the completed tube, for which operation very considerable power must be employed. The feeding mechanism must then be rapidly retracted whereby the consequent placing of a new hollow block upon the mandrel requires the expenditure of considerable power.

Provision for the changing requirements in connection with the hydraulic feeding mechanism hitherto employed could be made only by employing complicated controlling devices, and attention to them was troublesome, with the consequence that the apparatus was frequently put out of order. Furthermore, the solution of the problems involved in working by hydraulic means necessitates apparatus that is expensive, indeed it was usually necessary to install a special source of power for the feeding mechanism.

The present invention solves the practical difficulties in a simple and effective way.

According to the invention the carriage for the blank is driven by one or more electric motors in the use of gearing, in such manner that by graduating or dividing the drive the appropriate power and speed are exerted on the carriage.

It is particularly advantageous to use two electric motors for the drive, one of which runs at a high speed and does considerable work by advancing the blank to and withdrawing it from the mill, and also removing the blank from and replacing it on the mandrel, while the other motor, working at a considerably lower speed and doing far less

work, advances the blank during the rolling operation.

It is furthermore advantageous to arrange the motors in such manner that they can be put into and out of operation by an electrical switch or by coupling or uncoupling as desired.

In this way it is possible by the simplest means to operate the feeding mechanism with precision, under all working conditions. The work of supervising the plant is increased in considerable measure, but at the same time the cost of production is reduced. As compared with the known mechanism the control is very considerably simplified. The operator may, for example, by means of a press button, at any time reduce the speed or power applied to the feeding mechanism according to the particular operation of the moment, while watching the operation. In view of the simplicity of the whole arrangement the possible sources of error are reduced to a minimum.

The invention is illustrated diagrammatically in the accompanying drawings by way of example:

Figure 1 is a plan of the mechanism,

Figure 2 is an elevation,

Figure 3 is a partial side elevation, and

Figure 4 is a longitudinal sectional elevation, to an enlarged scale, showing the rear portion of the mechanism to which the invention relates.

The pilgering rolls are indicated by *a*. The blank or hollow block *b* is mounted upon a mandrel *b'*, which is loosely mounted on the carriage *d* with an automatic retracting device interposed. The carriage *d* comprises a cylinder having a piston the rod of which forms or is connected to the rifled spindle to which the mandrel *b'* is secured. The piston is subjected to air pressure by means of compressed air supplied from a suitable reservoir or container. Thus when the blank is worked by the rolls *a*, it is forced backwards against the air pressure and when released by the rolls is thrown forward by the air pressure acting upon the piston. The carriage *d* is moved upon guide rails by the means of spindles *c*.

The spindles *c* are moved by toothed wheels *e* mounted upon them, with which toothed wheels engage a pinion mounted upon the shaft of the motor *f*. *h* is the second driving motor connected through the clutch *g* to the motor *f* by means of a worm wheel drive *k*, the shaft of the motor *f* carrying the worm *k*, while the worm wheel *k* is, for example, mounted on a short shaft in alignment with the shaft of the motor *f* and adapted to be coupled thereto by the clutch *g*, or upon a sleeve carried by an extension of the shaft of the motor *f*, the sleeve being engaged therewith by the clutch *g*.

15 The mechanism is operated as follows:

15 The hollow block is first placed upon the mandrel. As for this purpose a great consumption of power is necessary, the operator switches in the more powerful motor *f*, and throws out the clutch *g*. After the hollow block has been placed in position, the same source of power feeds the blank at a considerable speed up to a position in front of the pilgering rolls. Here the current is passed through the motor *b* and the clutch *g* is engaged. Thereupon the motor *h*, which is now energized, drives the worm gearing *k*, *k*¹ and, through the clutch *g*, the shaft of the motor *f* with the armature and thus, through the toothed wheels *e* of the spindle *c*, moves the blank slowly forward through the pilgering rolls. If there are any interruptions during pilgering, that is to say, if the block should jam by reason of flaws in the metal, the blank may at all times be assisted over the difficult part by the motor *f*, or the blank may be quickly drawn back.

When the pilgering operation is completed the motor *h* is cut out and the more powerful motor *f* comes into operation and withdraws 40 the mandrel *b*' from the finished tube, retracts the feeding mechanism at a high speed and places a new hollow block upon the mandrel.

I claim:

45 1. Feeding mechanism for pilgering mills consisting in combination, a mandrel upon which the blank is applied, means comprising an electric motor adapted to cause the advancement of the said mandrel and its retraction from the pilgering rolls, a separate smaller electric motor adapted to advance the blank during the pilgering operation, and means whereby either motor may be set into operation to move the blank and the mandrel substantially as hereinbefore described.

2. Feeding mechanism for pilgering mills consisting in combination, a mandrel upon which the blank is applied, a carriage upon which the mandrel is supported and by which 60 the mandrel is advanced to and retracted from the pilgering rolls, gear through which power is applied to the said carriage, an electric motor adapted for the operation of the said gear in advancing the mandrel and 65 retracting it and in removing the finished

blank from and applying a new blank on the said mandrel, a second smaller electric motor adapted to advance the blank during the pilgering operation, and means whereby either motor may be set into operation to move the blank and the mandrel, substantially as hereinbefore described.

3. Feeding mechanism for pilgering mills consisting in combination of a mandrel upon which the blank is applied, a carriage upon which the mandrel is supported and by which the mandrel is advanced to and retracted from the pilgering rolls, gear through which power is applied to the said carriage, an electric motor adapted for the operation of the said gear in advancing the mandrel and reTRACTING it and in removing the finished blank from and replacing a new blank on the said mandrel, a second smaller electric motor adapted to advance the blank during the pilgering operation, and means comprising a clutch through which the drive may be imparted to the said gear from the second smaller electric motor, substantially as hereinbefore described.

OTTO BAMBERGER.
